UNITED STATES PATENT OFFICE

2,444,389

VENDING MACHINE

Frank A. Wagner, Vancouver, British Columbia, Canada

Application May 17, 1946, Serial No. 670,499

4 Claims. (CL 312—51)

1

This invention relates to a vending machine for newspapers, and the like, and more particularly, to the delivery mechanism useful in such vending machines to effect the dispensing of a single copy from the machine.

It is an important object of this invention to provide a vending mechanism for newspapers, and the like, which serially separates from an upstanding or upright group of such papers that are constantly urged forward against a lip, a single copy that is caused to hurdle the lip and be deposited downward for delivery to a customer, and which operates without injury to the paper and without requiring skill or great force on the part of the customer.

Another object of the invention is the provision of a delivery mechanism as described that is easily associated with coin-controlled actuation means of the standard type.

A still further object of the invention resides in the provision of a mechanism which may be produced simply at low cost, is rugged and has a long life, and which will withstand hard usage under the most adverse weather and other operating conditions.

The foregoing objects and others ancillary thereto, I prefer to accomplish as follows:

According to a preferred embodiment of my invention, I associate a manually-actuated dispensing mechanism in a casing and arrange that the mechanism be controlled to actuate by a coin-operable device. Specifically, the casing is of the type wherein newspapers, magazines, and the like, are positioned erect, preferably upon a forwardly inclined surface, in juxtaposition with the folds downward. In such position, the papers are urged forward toward a lower stop. Within the casing in front of such papers is mounted paper-engaging means carried by an arm, which when the arm is caused to swing, moves toward the papers and engages the front copy to carry it upward to hurdle the stop. Means is employed to rapidly withdraw the paper-engaging means from the paper, which is urged and falls into a chute for gravitational delivery to the customer. As the arm returns downward, it is again readied for a following operation.

A device unlocked by the deposit of the coin is usually employed to effect movement of the arm and the paper-engaging means, so that the operation of the machine depends upon the customer placing a coin into the machine before he may receive his copy of a paper or magazine. The mechanism is simple and may be constructed ruggedly so that it will last a long time under the

2

most adverse and undesirable operating conditions without more than minimum attention on the part of the operator.

The novel features that I consider characteristic of my invention are set forth with particularity in the appended claims. The invention itself, however, both as to its organization and its method of operation, together with additional objects and advantages thereof, will best be understood from the following description of a specific embodiment when read in connection with the accompanying drawings, in which:

Fig. 1 is a vertical sectional view through a newspaper vending machine showing, in three positions, the details of my dispensing mechanism; and

Fig. 2 is a perspective from below of an articulated arm construction employed in my dispensing mechanism.

Within casing 10 is positioned an inclined shelf 12, upon which the newspapers or magazines P are placed for dispensing. It will be noted that the magazines are mounted upright in juxtaposition with the primary fold F resting on the shelf 12. A stop lip 14 on the lower forward edge of shelf 12 prevents downward movement of the newspapers as they are urged forwardly by the follower plate 16, pivotally mounted on parallel arms 17, 17 that are forwardly urged by spring 18.

A window 20 in the upper part of the casing 10 permits a customer to view the front newspaper or magazine P. Below lip 14 are walls 22 and 24 spaced apart from each other and curved to form the delivery chute, down which the newspaper P, when being dispensed, falls and slides until it abuts the stop 16 on the lower forward edge of wall 22.

Across the machine, in front of the papers is a pivoted rock shaft 30, and a rock arm 32 thereabove, connected by a link 34 with the slider 36 in a coin chute 38. The coin chute is of the conventional type in which a deposited coin acts as a key between the slider 36 and the link 34, and permits the manual reciprocation of the latter. The link 34 is connected to arm 32 by a pin 33 and slot 35 forming a lost-motion connection necessitated by the swinging of the arm relative the straight line motion of the link 34.

Coins that have passed through the coin slide 38 fall out of the same within the casing 10 and into the receptacle 40 therebelow.

On the shaft 30, to swing upon rotation thereof, is mounted a link 42, having at its outer end a second link 44. The links 42 and 44 are pivoted together on shaft 46.

A pointed cam 50 on the shaft 46 presses against the cam follower 52 mounted on the spring 54, which in turn is supported on the shaft 30. This combination comprises a two-position indexing mechanism between the links 42 and 44, to hold them semi-rigid in the extended position of Fig. 2, or to hold and facilitate their return to the cocked position shown in dashed lines in Fig. 1. A separable cross bar 45 between the outer ends of links 44, 44, carries paper-engaging means, such as pins 47, which impale the papers or magazines being dispensed, and permit them to be lifted upward to hurdle lip 14 and to briefly accelerate the downward travel of such newspapers into the channel or passage between the walls 22 and 24.

When arms 42 and 44 are cocked, the stop bar 48 on arm 44 abuts the arms 42 and limits further collapsing.

The ends of bar 45 operate as cam followers with relation to the camming surface 60 mounted rigid with the casing 10. The bar ends press against surface 60 causing the links 42 and 44 to be extended from the cocked position to the substantially straight- or aligned-position. I consider the links 42 and 44 as comprising an articulated arm having a mid-joint and including a two-position indexing means to establish either a cocked or extended position.

Method of operation

When a customer places a coin in a latching position of the coin slide 36 so that pressure applied to the slider 36 can apply, in turn, pressure upon the link 34, the shaft 30, as it appears in Fig. 1, is caused to rotate in a clockwise direction about its axis and to cause link 42 to swing downward. Because of the engagement of the ends of bar 45 with the camming surface 60, the links 42 and 44 will be urged into substantial alignment and cocking action of the indexing mechanism, comprising cam 50 and follower 52, will be overcome. The cam 50 is turned relative the follower, and then snaps to hold the articulated arm in the position of Fig. 2. The coin will fall out of the slide 38 into the hopper 40.

Next, the customer pulls back on the slider 36, causing shaft 30 and arms 42, 44 to turn in a counterclockwise direction. Under such circumstances, bar 45 swings upward and the paper-engaging pins 47 impale themselves in the first copy of the newspaper group resting upon shelf 12, and tend to lift the same. As the first copy is raised above the edge of lip 14, the presser plate 16, operated by the spring 18, urges the following group of papers forward. Such action applies pressure on the bar 45 and links 44, 44. Since the links 42 continue in their counter-clockwise movement, and since additional weight will be applied to the bar 45 and the pins 47, the restraining action of cam 50 and follower 52 is overcome. In due course, the links 42 and 44 cock to the solid-line position of Fig. 1. This action is rapid and of a snap-retracting nature. It tends to snap the pins 47 out of the paper, and at the same time to apply a slight downward directing pressure against the impaled paper, so that it will be forcefully directed toward the chute between walls 22 and 24. Since chamber 70, which houses the dispensing mechanism is smaller than the chamber 12, in which the papers are positioned when the dispensed copy hurdles the stop 14, its ends come against wall faces 14 that merge with wall 24 therebelow. The coin slide is again in position to receive a coin. The paper falls down against the

75

stop 26 at the bottom end of the paper chute, where it can be easily grasped by a purchaser.

While I have shown and described particular embodiments of my invention, it will occur to those skilled in the art that various changes and modifications may be made without departing from the invention, and I, therefore, aim in the appended claims to cover all such changes and modifications as fall within the true spirit and scope of my invention.

Having thus described my invention, I claim:

1. In a vending machine for newspapers and the like, wherein the papers are positioned erect in juxtaposition with the fold downward, and are urged toward a stop active upon the lower folded edges, and over which the newspaper must be caused to hurdle: a pivot shaft in front and parallel to said papers, an articulated arm rigid on said shaft and directed generally toward said papers and comprising a pair of links, paper-engaging means carried by said arm, a two-position indexing mechanism between said links, lever means to rotate said shaft and swing said arm when the links are in substantial alignment toward said papers and upward, the forward urge on said papers serving to operate the indexing mechanism to break the articulated arm, means to move the arm downward, and guide means to substantially realign said links and to reversibly operate the indexing mechanism.

2. In a vending machine for newspapers and the like, wherein the papers are positioned erect in juxtaposition with the fold downward, and are urged toward a stop active upon the lower folded edges, and over which the newspaper must be caused to hurdle: an articulated arm mounted in front of said papers to swing and comprising a pair of links, paper-impaling means carried by said arm, a two-position indexing mechanism between said links, means to swing said arm when the links are in substantial alignment toward said papers and upward, the forward urge on said papers serving to operate the indexing mechanism to break the articulated arm, means to move the arm downward, and guide means to substantially realign said links and to reversibly operate the indexing mechanism.

3. In a vending machine for newspapers and the like, wherein the papers are positioned erect in juxtaposition with the fold downward, and are urged toward a stop active upon the lower folded edges, and over which the newspaper must be caused to hurdle: an articulated arm mounted in front of said papers to swing and comprising a pair of links, paper engaging means carried by said arm, a two-position resilient cam-and-follower indexing mechanism between said links, means to swing said arm when the links are in substantial alignment toward said papers and upward, the forward urge on said papers serving to operate the indexing mechanism to break the articulated arm, means to move the arm downward, and guide means to substantially realign said links and to reversibly operate the indexing mechanism.

4. In a vending machine for newspapers and the like, wherein the papers are positioned erect in juxtaposition with the fold downward, and are urged toward a stop active upon the lower folded edges, and over which the newspaper must be caused to hurdle: an articulated arm mounted in front of said papers to swing and comprising a pair of links, paper-engaging means carried by said arm, a two-position indexing mechanism between said links, means to swing said arm when

the links are in substantial alignment toward said papers and upward, the forward urging on said papers serving to operate the indexing mechanism to break the articulated arm, means to move the arm downward, and guide means to substantially realign said links and to reversibly operate the indexing mechanism.
